US0D1110086S

(12) **United States Design Patent** (10) **Patent No.:** **US D1,110,086 S**
(45) **Date of Patent:** **** Jan. 27, 2026**

(54) **TABLE**

(71) Applicant: **Williams-Sonoma, Inc.**, San Francisco, CA (US)

(72) Inventor: **Dino Lauando**, Queens, NY (US)

(73) Assignee: **Williams-Sonoma, Inc.**, San Francisco, CA (US)

(**) Term: **15 Years**

(21) Appl. No.: **29/964,046**

(22) Filed: **Sep. 20, 2024**

(51) **LOC (15) Cl.** **06-03**

(52) **U.S. Cl.**

USPC **D6/692.3**

(58) **Field of Classification Search**

USPC D6/334, 336, 337, 338, 344, 349, 352, D6/355, 360, 365, 366, 374, 375, 376, D6/379, 380, 385, 685, 687, 689, 690, D6/691, 691.5, 692, 692.3, 692.4, 702, D6/707, 707.19, 707.2, 707.22, 708.15, D6/708.16, 708.17, 708.2, 709, 709.18, D6/709.2, 709.21

(57) **CLAIM**

The ornamental design for a table as shown and described.

DESCRIPTION

FIG. 1 is a perspective view of the table;

FIG. 2 is a front elevational view of the table;

FIG. 3 is a rear elevational view of the table;

FIG. 4 is a left side elevational view of the table, the right side of which is a mirror image;

FIG. 5 is a top plan view of the table; and,

FIG. 6 is a bottom plan view of the table.

The broken line portions of the drawings are included to show portions of the table that form no part of the claimed design.

1 Claim, 6 Drawing Sheets
